STEERING WHEEL

Roger E. Geller, Dayton, Ohio, assignor to General
Motors Corporation, Detroit, Mich., a corporation of
Delaware

Filed Oct. 23, 1963, Ser. No. 77,115

Term of patent 7 years

(Cl. D14—30)

FIGURE 1 is a perspective view of a steering wheel showing my new design;

FIGURE 2 is an elevational view taken on a reduced scale.

I claim:

The ornamental design for a steering wheel, as shown.
